CLAIM

The ornamental design for a sensor assembly, as shown and described.

DESCRIPTION

FIG. 1 is a perspective view of a sensor assembly.

FIG. 2 is another perspective view thereof.

FIG. 3 is a front view thereof.

FIG. 4 is a rear view thereof.

FIG. 5 is a right view thereof.

FIG. 6 is a left view thereof.

FIG. 7 is a top view thereof.

FIG. 8 is a bottom view thereof.

FIG. 9 is a perspective view of a vehicle including a sensor assembly.

FIG. 10 is another perspective view of a vehicle including a sensor assembly; and,

FIG. 11 is a top perspective view of a portion of a vehicle including a sensor assembly.

The broken lines illustrated in FIGS. 9–11 are included for the purpose of illustrating environmental structure while all other broken lines illustrate non-ornamental aspects of the sensor assembly; the broken lines form no part of the claimed design.

1 Claim, 11 Drawing Sheets
